UNITED STATES PATENT OFFICE.

JESSIE CARR TYNDALL, OF ST. LOUIS, MISSOURI.

DESIGN FOR AN AUTOMOBILE RADIATOR CAP.

Application filed January 16, 1926. Serial No. 16,122. Term of patent 7 years.

To all whom it may concern:

Be it known that I, JESSIE C. TYNDALL, a citizen of the United States, residing at St. Louis, State of Missouri, have invented a new, original, and ornamental design for an Automobile Radiator Cap, of which the following is a specification, reference being had to the accompanying drawing, forming part thereof.

The figure is an elevation of my new design for automobile radiator cap.

The device is substantially of a conical shape and presents substantially the same appearance when viewed from any angle.

I claim:

The ornamental design for an automobile radiator cap, as shown and described.

JESSIE CARR TYNDALL.
